UNITED STATES PATENT OFFICE

FRANK R. CHESTER, OF NEW YORK, N. Y., ASSIGNOR TO CHESTERFIELD CONTROL COMPANY, OF DOVER, DELAWARE, A CORPORATION OF DELAWARE

INTERMITTENT DRIVE MECHANISM

Application filed March 5, 1927. Serial No. 173,194.

This invention relates to an improved intermittent drive mechanism.

It is an object of the invention to provide a device of this character embodying a relatively simple construction readily assembled to operate automatically over long periods of time with freedom from electrical or mechanical difficulties.

It is a further object of the invention to provide such a device as will consume a minimum amount of current.

Other objects of the invention will in part be obvious and will in part appear hereinafter.

15 The invention accordingly comprises the features of construction, combination of elements and arrangement of parts which will be exemplified in the construction hereinafter set forth, and the scope of the application of 20 which will be indicated in the claims.

For a fuller understanding of the nature and objects of the invention reference should be had to the following detailed description taken in connection with the accompanying 25 drawings, in which:

Figure 1 is a partly sectional side view of one form of mechanism embodying the improved construction of the present invention;

Fig. 2 is a similar view taken from the 30 opposite side;

Fig. 3 is an end elevation thereof;

Fig. 4 shows diagrammatically the circuit involved; and

Fig. 5 shows a form of circuit-breaker 35 which may be embodied in the mechanism.

In the embodiment illustrated a pair of spaced side walls 10 are retained against movement with respect to each other by means of cross-bars 11 extending therebetween. These walls mount a base or shelf 12 and a rotatable shaft 13. In the present instance a disk 14 is secured to this shaft and is formed with a series of notches 14' providing in aggregate an annular ratchet.

40 Mounted to oscillate upon this shaft is a lever having one arm 15 extending outwardly and to a point beyond the periphery of the disk 14; its opposite arm 16 being comparatively short and pivotally secured to the upper end 45 of a pair of spaced links 17, the lower end of

which is pivotally secured to a lever 18, in turn having its inner end rockingly mounted upon a shaft 19 extending between the side walls 10. Mounted upon the base 12 is an electromagnet 20, above which an armature 21 is movably mounted by having the inner end thereof rockingly secured to a shaft 22 extending between the side walls, the outer end of this armature being link-connected as at 23 to the lever 18.

Thus it is obvious that when the circuit is closed through the electromagnet 20 the armature 21 will be attracted; and by means of the leverage or linkage system employed the relatively short travel of the armature 55 will be multiplied, resulting in a pronounced travel of the outer arm 15 of the lever which is mounted to rock upon the shaft 13.

In order that this movement may result in motion being imparted to the shaft 13 the 60 outer end of the arm 15 may carry a spring-pressed pawl 24, which overlies the periphery of the disk 14 and is engageable with one of the notches 14' to prevent relative movement of these elements in one direction; it 65 being obvious that in the embodiment illustrated, and as viewed in Fig. 1, when the arm 15 moves in a clockwise direction lost motion will result between the pawl and ratchet. In the present instance a spring 70 of the contraction type has its upper end secured to the arm 15 and its lower end fixedly connected as at 26 to the side walls of the motor. Furthermore, it is preferred that a 75 pawl 27 be carried by the side walls and, consequently, bear within one of the notches 14' when they come to sequentially lie adjacent its outer end, thus preventing—as in Fig. 1—a clockwise movement of the disk 14. It will 80 also be observed that, as shown, the disk carries a series of pins 28 corresponding in 85 number to the number of notches therein, and the lever 18 rigidly supports a hook-shaped member 29, which, as shown in Fig. 2, bears against one of these pins to prevent clockwise 90 movement of the disk and shaft 13 (as viewed in Fig. 1) with the parts in the position shown in Figs. 1 and 2.

At this time it will be understood that with the parts in position movement of the shaft 13 100

in either direction is prevented, for the reason that the pawl 27 will prevent clockwise movement thereof, and the pawl 29 counterclockwise movement. However, if the circuit through the electromagnet is closed the arm 15 will swing upwardly to a point at which the pawl 24 engages the next succeeding notch of the annular series. During such swinging movement it will be obvious that the pawl provided by the hook-shaped member 29 will move to a point at which it no longer intersects the path of travel of the pin 28 adjacent which it lies, and that movement of the disk and shaft 13 incident to the frictional contact of the periphery of the latter with the pawl 24 will be prevented by virtue of the pawl 27. If the circuit is now interrupted the spring 25 will move the arm 15 downwardly, carrying with it the disk and shaft 13; the hook-shaped member again assuming the position shown in Figs. 1 and 2 and acting as a stop to the movement of the disk through a distance greater than the distance between two notches.

In the illustrated type of machine, in order that the circuit may be broken immediately upon the pawl 24 shifting to a position at which it engages the next notch of the series, a circuit-breaker is provided which may be of the type shown in Fig. 1, or schematically and diagrammatically illustrated in Fig. 5. In the first of these figures the numeral 30 indicates a lead connected with one of the coils of the electromagnet, which coil is connected with the second coil, and from which latter a lead 31 extends. This lead is connected with a spring member 32 having a bowed portion 33. A block of suitable insulating material 34 is mounted between the walls 10 and pivotally carries between arms 34 a lever 35 formed of conducting material and having its rear end in sliding engagement with the spring 32, which bears against the same adjacent the bowed portion thereof. The forward end of this lever extends between the link 17 and may be engaged by either cross-pins 36 or 37; the former acting as a stop and shifting member, and the latter being of conducting material and connected with a lead 38.

Presuming that current is flowing through the leads 30-38, and with the position of the parts as shown in Figs. 1 and 2, it will be obvious that the arm 15, as aforescribed, will swing upwardly. During such swinging movement the lever 35, by virtue of contacting with the pin 37, will be swung downwardly, such movement being resisted by the spring 32. At a certain interval of the movement of this lever, however, that end thereof which is engaged by the spring will pass the "dead center" of the curved portion 33 thereof, and thereupon the spring, instead of resisting the movement of the lever, will accelerate it to such an extent that the end thereof

which engages the pin 37 will move out of contact therewith and snap into contact with the pin 36, thus interrupting the circuit. As the parts assume their normal position under the influence of the spring 25 or other provision to reestablish such normal position, the pin 36 will bear against the lever 35 until the rear end of the latter again moves past the "dead center" portion 33 of the spring and snaps into contact with the pin 37, so that when current again flows through the leads 30-38 a repetition of the foregoing operation will occur.

In the second form of circuit-breaker, shown in Fig. 5, by means of which the same result may be achieved, the links 17 or other suitable moving portion of the motor carry a U-shaped member 39, at least a portion of which is formed of conducting material, and one arm 40 of which is preferably shorter than the second arm 41 thereof. This member is pivotally mounted as at 42, and a spring 43 connected therewith may serve normally to tilt the arms thereof at an angle to either side of the longitudinal axis of the links 17 or other elements supporting this member. One lead 44 is connected with this member, and a lead 45 is connected with a contact arm 46 mounted adjacent the path of travel of the arm 40, and the position of which contact arm may be established by a yielding anchorage 47. Mounted adjacent the path of travel of the arm 41 is a plate 48 carrying spaced pins 49 disposed one adjacent each of the upper and lower edges of the arm 41, and the plate may be shifted outwardly or inwardly, as, for example, by an adjusting mechanism 50. The spring 43 will act to hold the arm in contact with the member 46, thus maintaining the circuit closed, and the circuit will continue to be energized during the descent of the links 17 and until the arm 41 has engaged the lowermost pin 49 for a sufficient length of time during such descent to cause the arm 40 to swing clear of the contact member 46. A quick break of the electrical connection between these parts is assured, first, by the spring 43, and second, by the spring 47; it being obvious that incident to the adjustment afforded at 50 the interval of contact between the energized members of the circuit-breaker may be varied by shifting the plate 48 inwardly or outwardly, as desired, and the length of the stroke of the armature may be varied accordingly.

Secured to the disk 14 as at 51 is a second circuit-maker or breaker, including in the embodiment illustrated a plate 52 having radially-extending contact arms 53 corresponding in number to the number of notches 14'; these arms, as in Fig. 3, being divided into two series, and adjacent arms being of different series. As will be observed furthermore in this figure, according to the

present construction the periphery of the plate 52 is grooved, as has been indicated at 54, and a block 55 mounts brushes 56, 57, 58, the first of which extends, in the present instance, into this groove. The second brush is arranged in the path of travel of the contact arms 53 of the innermost series, and the third is disposed in the path of travel of the contact arms of the outermost series. 10 Thus, by this construction or its equivalent the plate 52 will at all times be in electrical contact with the brush 56; and when the parts are in a position of rest, an arm 53 of one or the other series will be in contact 15 with one of the two outer brushes.

Referring to Fig. 4, the lead 38 is connected to the body of a thermostatic strip 59, which carries at its outer end a contact 60 optionally engageable with either the contact 61 or contact 62. This assembly may be carried upon the lower face of the base 12 or otherwise conveniently positioned. The contact 61 is connected with the brush 57, and the contact 62 with the brush 58. 20 Power leads 63—64 extend from a suitable source of electrical energy, the latter lead being continued in the form of the lead 30 and having a branch lead 65 with which a heating coil 66 encircling the thermostatic strip 59 is connected, this lead being continued as at 67 to the contact member 61. The lead 63 extends to and is connected with the brush 56.

The thermostatic strip 59 is so constructed and disposed with respect to the contact members 61—62 that, when under normal temperature, it will engage the contact 62. On the other hand, under the action of heat from the coil 66 it will move to engage the contact 61. Considering the parts to be in the position shown in Figs. 1 to 4, with current flowing through the leads 63—64, the current will flow from the lead 64 through lead 30, electromagnet 20, lead 31, the circuit-breaker (the parts of which are in closed position), lead 38, thermostatic strip 59, contacts 60—61, brush 57, a contact arm 53 of the innermost series, plate 52, brush 56, and so through lead 63. Additionally, 40 current will flow from lead 64 through lead 65, the heating coil 66, lead 67, brush 57, plate 52, brush 56 and lead 63, thus closing the circuit through the heater and forcing the thermostatic strip to a position at which the contacts 60—61 are engaged as afore-described.

As a consequence of this closing of the circuit, the electro-magnet will act to attract the armature 21, resulting in an upward movement of the arm 15 and breaking of the circuit through the electro-magnet and a downward movement of the arm 15 translated into rotation of the disk 14 and shaft 13 secured thereto, all as aforescribed. Simultaneously with such rotation, and while

the circuit-breaker is still open, the contact arm 53 of the inner series which has been engaged by the brush 57 will move to a position at which these parts are no longer in electrical contact, a succeeding arm of the outermost series moving into contact with the brush 58. Under these conditions, and with the closing of the primary circuit-breaker, it will be obvious that a circuit will not be completed, for the reason that the contact is broken between the brush and the arm 53 of the innermost series. This will have the secondary result of current not passing through the lead 65 and the heating coil 66, and the thermostatic strip 59 will accordingly cool and swing back to its normal position, at which its contact 60 engages the contact 62. Under such conditions current will flow through the brush 58, a contact arm 53 of the outermost series, brush 56 and lead 63, whereupon the electromagnet once more will be energized, the disk 14 and shaft 13 will be rotated, and the position of the parts shown in the drawings will be reestablished, resulting in the heater coil 66 causing the thermostatic strip contact 60 to move toward the contact 61 to repeat this operation ad infinitum.

Thus, in the embodiment illustrated the interval between actuations of the shaft 13 is governed by the time necessary for the contact 60 carried by the thermostatic strip to move out of engagement with one of the adjacent contacts and into contact with the other, the circuit being closed by means of these contacts and being broken by the primary breaker aforescribed; the secondary breaker embracing, in the present instance, elements 52 to 58 inclusive, and serving, first to prevent a reestablishment of the circuit upon the substantially immediate closing of the first circuit-breaker, and second, controlling the current flow through the heating coil. In this connection it will be understood that the secondary breaker includes two switch mechanisms operating alternately or inversely, i. e., one being open when the other is closed.

Obviously, a driving mechanism of this type lends itself to numerous different uses, and, according to the present embodiment, the movement of the shaft beyond predetermined positions is prevented by the pawl mechanisms provided for this purpose. The motor herewith suggested will be drawing an appreciable amount of current only during that interval of time when the arm 15 is being swung upwardly, and this interval preferably will be only a minute proportion of the total period of time during which the mechanism is operated.

Thus, among others, the objects of the invention have been accomplished, and since certain changes may be made in the above construction and different embodiments of

the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described and all statements of the scope of the invention which as a matter of language might be said to fall therebetween.

Having described my invention, what I claim as new and desire to secure by Letters Patent is:

1. An intermittent drive mechanism, including a shaft, an electromagnet, means actuated by said magnet to drive said shaft, circuit-breakers connected with each other and with said magnet, means connecting said shaft with said circuit-breakers to operate the same successively, a circuit-closing member connected with said breakers and magnet and including a thermostatic strip, means connected therewith to close the circuit, and a heating means adjacent said strip and controlled by one of said circuit-breakers.

2. An intermittent drive mechanism, including a shaft, an electromagnet, means actuated by said magnet to drive said shaft, circuit-breakers connected with each other and with said magnet, means connecting said shaft with said circuit-breakers to operate the same successively, a circuit-closing member connected with said breakers and magnet and including a thermostatic strip, a pair of spaced contacts, means associated with said strip to close the circuit through said electromagnet by engaging with either of said contacts, and a heating coil associated with said strip and connected with one of said breakers.

3. An intermittent drive mechanism, including an electromagnet, a shaft, means connected with said magnet to be actuated thereby and drive the shaft, a circuit-breaker connected with said shaft to be operated thereby, means for closing the circuit-breaker, a thermostatic strip, a second circuit-breaker operated by said shaft, means controlled by said thermostatic strip connected with said electromagnet to close the circuit therethrough, and a heating coil in association with said strip and connected with said second breaker to control the operation of said strip.

4. An intermittent drive mechanism, including a rotatable shaft, an electromagnet, means connecting said magnet with said shaft to drive the latter, a circuit-breaker connected with said magnet and said last-named means to be actuated by the latter to interrupt the circuit through the magnet, a second interrupting mechanism connected with said shaft and including a pair of alternately

timed circuit-breakers connected with said first-named breaker, a thermostatic strip, means connected therewith to close the circuit through one of said last-named breakers, and means controlled by said latter breakers and governing the operation of said strip.

5. An intermittent drive mechanism including a motor, a thermostatically operated switch, a shaft forming a part of said motor, two series of circuit breakers alternately operated by said shaft, a heating element disposed adjacent the thermostatic member of said switch and connected to one series of said circuit breakers to be periodically energized therethrough, and said circuit breakers being connected to said motor.

6. An intermittent drive mechanism including a motor, a thermostatically operated switch, a shaft forming a part of said motor, two series of circuit breakers alternately operated by said shaft, a heating element disposed adjacent the thermostatic member of said switch and connected to one series of said circuit breakers to be periodically energized therethrough, said circuit breakers being connected to said motor, and a further switch operated by said motor to render said first named switch inoperative during its circuit-opening operations.

In testimony whereof I affix my signature.

FRANK R. CHESTER.
